[57] **CLAIM**

The ornamental design for a portion of a strike face for a golf club head, as shown and described.

DESCRIPTION

FIG. 1 is a front perspective view of the first embodiment of the portion of a strike face for a golf club head of the present invention;

FIG. 2 is a front elevational view thereof;

FIG. 3 is a top elevational view thereof;

FIG. 4 is a front perspective view of a second embodiment of the portion of a strike face for a golf club head of the present invention;

FIG. 5 is a front elevational view of the second embodiment; and,

FIG. 6 is a top elevational view of the second embodiment. In the first embodiment shown in FIGS. 1-3, the portion of a strike face for a golf club head and the surrounding area are not shown in color. In the second embodiment shown in FIGS. 4-6, the portion of the strike face for a golf club head is copper in color, which is represented by cross hatching and the surrounding area is black in color, which is represented by stippling.

The broken line showing a golf club head is for illustrative purposes only and forms no part of the claimed design.
